UNITED STATES PATENT OFFICE

JACOB L. KLEINMAN, OF NEW YORK, N. Y.

SLIDING AND SWINGING WINDOW

Application filed October 2, 1928. Serial No. 309,762.

This invention relates generally to metal windows and more particularly to such windows that are adapted to slide up and down and be swung inwardly.

5 A primary object of the present invention is to permit the inward opening of a window having three sashes disposed in the same horizontal plane.

Another object is to prevent binding or 10 jamming at the meeting edges.

Still another object is to center the glass pane.

A still further object is to prevent the putty from falling away from the glass 15 pane.

Another object is to prevent the metal parts from touching each other in their movements.

20 A still further object is to guide the parts in position when assembling.

A further object is to make the window weatherproof.

Another object is to provide a window 25 that is simple in construction, economical to manufacture and durable in use.

Other objects are to permit easy movement of the parts, and to strengthen the various parts of the window.

30 Other objects and advantages of my improved window will appear from the description thereof to follow taken in connection with the accompanying drawings in which—

35 Figure 1 is an elevation of a window embodying my invention, looking at the same from the interior of the room.

Figure 2 is a perspective view of the lower sliding frame showing the sashes in 40 opened position.

Figure 3 is a horizontal sectional view taken on the plane indicated by the line 3—3 of Figure 1.

45 Figure 4 is a detail view of one end of the channel portion of the sliding frame.

Figure 5 is a detail view showing how the sliding frames are assembled or disassembled.

50 Figure 6 is a sectional view on the plane indicated by the line 6—6 of Figure 1.

Figure 7 is a detail view of a removable plate.

Figure 8 is a sectional view on the plane indicated by the line 8—8 of Figure 1.

Figure 9 is a perspective view on the top 55 sill showing a portion of the side post or jam.

Figure 10 is a detail view of a section of the side post or jam showing the slots for the sliding frames and the opening for inserting the ends of said frames. 60

Figure 11 is a sectional view taken on the plane indicated by the line 11—11 of Figure 1.

Figure 12 is a detail view showing the construction of the sash frame at its edge near the side jam. 65

Figure 13 is an enlarged sectional view of the side post or jam and showing the relative positions of the sliding frames and 70 sashes.

Figure 14 is an enlarged detail view of a portion of the side post or jam.

Figure 15 is an enlarged detail view showing the handle for raising or lowering the 75 window.

Figure 16 is an enlarged perspective view of a portion of the sliding frame and sash mounted thereon.

Figure 17 is an enlarged detail view of 80 one end of a sliding frame showing how the window chain is mounted.

Figure 18 is a detail view of the locking means.

Referring to the various views of the 85 drawings in detail, the window here shown comprises a bottom sill 20, an upper sill 21 and side posts or jams 22, all of which are formed of metal or other suitable material. Adapted to slide up and down between said 90 side posts 22 is an upper sash frame 23 and a lower sash frame 24. Mounted in the upper sash frame 23 and adapted to be swung inwardly are sashes 25, 26, and 27, and mounted in the lower sash frame 24 and 95 adapted to be swung inwardly are sashes 28, 29 and 30.

Referring to Figure 11, the bottom sill 20 is formed with a slanting surface 31, a depressed portion 32 and a curved bead 33. 100

With particular reference to Figure 9, the upper sill 21 consists of a rectangular shaped box member 34 consisting of a bottom plate or wall 35, side walls 36 and an upper wall 37. The free edges of the side walls 36 are inwardly curved to form a loop 38, and the upper wall 37 has inwardly curved flanges 39 formed on its edges, which flanges 39 are adapted to be inserted into the loops 38, the inwardly curved portion of the loops 38 holding the wall 37 and side walls 36 securely together. The bottom wall 35 is provided with a longitudinal slot 40, extending from a point remote from one end to a point remote from the opposite end, the walls 40' of said slot being curved toward each other to restrict said slot, the end portions of said wall 35 forming a solid base for mounting pulleys. A pair of aligned openings 41 are formed in the bottom wall 35 for a purpose which will be described.

The window frame is of sufficient dimensions to enclose the upper and lower sashes of the present construction. The window construction embodies a rectangular frame for the upper sash and a rectangular frame for the lower sash which move in different grooves in the window frame and these frames are adapted to slide past each other. Each sash frame carries three hinged units or sections in which the transparent members or glass panes are mounted. In referring to the sashes as upper and lower sashes I refer to the upper one as the one which is disposed in the higher position when the window is entirely closed, and to the lower one as that which is in the lower-most position when the window is closed, although both sashes are adapted to slide vertically and at times they may be reversed in this relation.

Referring to Figure 13, the vertical casement posts 22 are hollow in construction and each consists of an inner side wall 42, an outer side wall 43 and a front wall 44, all of which walls are formed integrally. The front wall 44 is formed with a depressed portion 45 which forms a channel 46 for the reception of the sliding frames as will be hereinafter described. This depressed portion 45 includes a shouldered portion 47, an inwardly extending flange portion 48, a curved portion 48', and an inwardly slanting portion 49 which terminates in a flat portion 49'. The outer side wall 43 is formed with an offset rectangular extension 50 to form a guide for placing the window into the opening in the wall structure. Screwed to the face of the front wall 44 is a plate 51, the inner end of said plate extending to about midway of the channel 46 and terminating in a curved grooved portion 52. The outer end of said plate 51 is formed with a curve corner 52', the edge of

said corner serving as a guide in assembling the parts and its curved contour presenting a pleasing appearance and also preventing sharp corners at this point. Another plate 53 is screwed to the outer face of the depressed portion 45 and includes a flange portion 54, a curved extension 55, a straight portion 56 disposed at right angles to said curved portion 55, and terminating in a curved grooved portion 57, said grooved portion 57 disposed in the same horizontal plane as the groove portion 52 of the plate 51. Said curved grooved portion 57 with the curved portion 48' of the plate 45 forming a restricted passageway or slot 57'. The curved portion 52 and the curved portion 55 also form a restricted passageway or slot 55'. The inner edges of the inner and outer walls, 42 and 43, respectively, are formed with inwardly curved looped portions 56. Joining the side walls and serving as a rear wall is a plate 57, which plate is bent over upon itself at about midway its length to form a flange 58 to strengthen the said plate, and provide additional locking means to prevent displacement from the wall structure. The side edges of the rear wall plate 57 are hooked inwardly as indicated at 59 and said hooked edges snugly and releasably engage the looped portions 56 of the side walls and prevent displacement of the parts.

Referring particularly to Figures 2, 16 and 17, the sliding frames will now be described. Each sliding frame comprises an upper horizontal cross bar member indicated generally at 60 and including upper and lower walls 61 and 62, respectively, and a vertical web portion 63, said walls and web portion forming a channel 63'. From Figure 17, it will be noted that the upper and lower walls 61 and 62, respectively, terminate at a point removed from the end of the web portion 63, said walls ending in a curved end portion 61'. An opening 62' is formed in each of said walls adjacent their curved ends, the opening in the upper wall 61 being of larger diameter than the opening in the lower wall 62. Formed integrally with the web portion 61 and disposed at an angle thereto is a plate or extension member 64 and formed on the end of said extension and disposed at an angle thereto is a flange 65. Punched in the horizontal bar member 60 at spaced intervals are holes 66 for a purpose which will be explained hereafter. Each sliding frame is also provided with a lower horizontal bar member 67 similar in construction to the horizontal bar member 60. Joining the upper and lower horizontal cross bar members at each end thereof is a post or housing indicated at 68, said post consisting of side walls 69 and a curved outer wall 70, said

walls forming a channel 70' for a purpose which will appear.

With reference to Figure 11, the construction of the lower sashes 28, 29 and 30 will now be described. Each of said sash sections is provided with an upper cross bar member 71 formed of angle iron and comprising horizontally disposed upper and lower walls 72 and 73, respectively, and a vertically disposed web 74 joining said walls. A groove 74' is formed between the web portion and the upper and lower walls. The upper wall 72 has an offset extension member 75 forming a shouldered portion 76, a groove 75', and said extension terminating in a downwardly extending flange 77. Integrally formed on the lower wall 73 is a downwardly extending flange 78 which terminates in an inwardly extending slanting edge 79. Fixed to the under surface of the lower wall 73 is an L-shaped plate 80 provided with an inwardly slanting edge 81.

Each of said lower sashes 28, 29 and 30 is provided with a lower horizontal cross bar member 82 consisting of an upper wall 83 and a lower wall 84 joined together by a web 85, each web portion 85 provided with a depressed portion forming grooves 86 between said web and said upper and lower walls. The upper wall 83 has formed thereon an integral upstanding flange 87 which terminates in an inwardly slanting edge 88. Fixed to the upper surface of said upper wall 83 is a plate 89 provided with an upstanding flange 90 which terminates in an inwardly slanting edge 91. The lower wall 84 has a plate 92 secured thereto, said plate 92 having a downwardly extending flange 93 provided with an inwardly extending flange portion 94. Also formed integrally with said lower wall 84 is an extension member comprising a downwardly extending flange 95 and a plate 96 disposed at a slight angle to the horizontal. Said plate 96 terminates in a hook portion 97 which forms a pocket 98. This extension member and plate 92 with its flange 94 form a chamber 99 as will be readily seen from Figure 6.

An important feature of the present invention is the novel means for preventing the jamming of the meeting edges such as where the lower part of the upper sash and the upper part of the lower sash meet, and where the lower part of the lower sash meets the lower sill. This means is clearly illustrated in Figures 6 and 11. Carried by the lower cross bar member of the lower sashes and mounted in the chamber 99 is a piece of metal 100, substantially S-shaped in cross section, and which is preferably made of zinc or other flexible material and which extends the entire length of the chamber. One end of this strip 100 is re-

leasably and replaceably held in the pocket 98 formed by the hook 97, and the other end thereof rests freely on the upper surface of the inwardly extending flange 94, permitting a horizontally disposed curve portion 101 thereof to extend below the lowermost plane of the hook 97 and permitting the vertically disposed curved portions 102 and 103 to extend inwardly toward each other to form a restricted passageway. As will be understood as the lower sash is pushed downwardly with its metal strip 100, the curved portion 101 comes in contact with the depressed portion 32 of the lower sill 31 and thereby cushions the movement at this point, and the curved portions 102 and 103 come in contact with the beaded portion 33 of the lower sill and also help to cushion the movement and forming an air tight junction. The hook 97 and flange 85 portion 94 in addition to holding the metal strip 100, also form a flat bearing surface for resting against the sill thus eliminating injury to the sill from contact with sharp edges or corners. As this strip 100 is formed of flexible material it tends to give and conforms readily to the conditions present when the sill is closed.

Referring to Figures 8 and 11, the upper sashes 25, 26 and 27 which are mounted in the upper frame 25 are constructed substantially the same and their points of similarity will now be described. Each sash has an upper cross bar member 104 formed of angle iron and consisting of horizontally disposed upper and lower walls 105 and 106, respectively, and a vertically disposed web portion 107 joining said upper and lower walls, said web portion being depressed to form grooves 108. Integrally formed on the edge of the upper wall 105 is an extension 109 adapted to enter the slot 40 and due to the inwardly curved walls 40' of said slot forming a restricted opening at this point, said extension 109 snugly engages said walls and forms an air tight juncture at this point, and permits the upper wall 105 of the cross bar member to snugly engage the under surface of the lower wall 35 of the upper sill. Integrally formed on the edge of the lower wall 106 is a downwardly extending flange 110 which terminates in an inwardly inclined edge 111. Secured to the lower surface of the lower wall 106 is a plate 112 provided with a downwardly extending flange 113 which terminates in an inwardly inclined edge 114.

As will be apparent from Figure 11, each sash section 25, 26 and 27 has a lower cross bar member 115 formed of angle iron and consisting of horizontally disposed upper and lower walls 116 and 117, respectively. Joining the upper and lower walls is a vertically disposed web portion 118, which web portion is formed with a depressed portion 119. Formed integrally

with the upper wall 116 and extending upwardly therefrom is a flange 120 which terminates in an inwardly slanting edge 121. Secured to the upper surface of the upper wall 116 is a plate 122 provided with an upstanding flange 123 which terminates in an inwardly slanting flange 124. Fixed to the depressed portion of the web portion 118 is a plate 125. This plate 125 is formed with a shelf portion 126 and an upstanding flange portion 127 disposed at right angles to said shelf portion. The upstanding flange portion 127 terminates in an inwardly extending flange 128. The plate 125 is so mounted on the web portion 118 and its shape is such that a pocket 129 is formed between said web portion and said plate as will be seen from Figure 11.

Carried by the lower cross bar member 115 of the upper sash is a strip 130 of flexible material such as zinc or bronze of substantially S-shape in cross section. This strip 130 is mounted in the pocket 129 and has one end releasably held between the plate 125 and the shouldered portion of the web formed by the depressed groove 119, and the other end extends upwardly freely in said pocket 129, its free end disposed underneath the inwardly extending flange portion 128 of the plate 125. When the sash sections are in closed position as shown in Figure 11, the flange portion 128 of the lower portion of the upper sash snugly engages the extension 75 of the upper portion of the lower sash, and the flange portion 77 extends into the pocket 129 and engages the curved portion 131 of the strip 130. It will be noted that there is plenty of room between the free end of the strip 130 and the flanged portions 127 and 128 to permit the strip to flex or give when the flange portion 77 engages the said strip. This strip 130 and the strip 100 when they become worn or deformed may be readily replaced with new fresh strips merely by sliding them out sidewise without removing any of the parts of the window sections.

Referring to Figure 12, the side vertical edges of the sashes 25, 28, 27 and 30 which are connected to the side posts 22 will now be described. Joining the upper and lower cross bar members of both the upper and lower sashes at the ends positioned near the side posts 22 is a plate 132 including a flat portion 133 and an inwardly curved flange 134 of the same angle as the flanges 111 and 121 of the upper sashes and the flanges 79 and 88 of the lower sashes. It will be noted from Figures 2 and 16 that the length of the flanged portion 134' is shorter than the distance between the cross bars 60 and 67, permitting it to travel freely between same and permitting the sashes to swing. The other end of the plate 132 has formed thereon an integral curved flange portion 134'.

Secured to the plate 133 is an angle plate indicated generally at 135 and consisting of a bottom flat portion 136, a side wall 137 and top wall 138 which terminates in an inwardly slanting flange portion 139 disposed in the same angle as the flanges 114 and 124 of the upper sash and flanges 81 and 91 of the lower sash.

With reference to Figures 2 and 3, the opposite vertical edges of sashes 27 and 30 which extend outwardly when the sashes are opened will now be described. Joining the upper and lower cross bar members of both of said sashes 27 and 30 is a plate indicated generally at 140 consisting of a flat portion 141 bent upon itself to form a flange 142 comprising a double thickness of material and extending at right angles to the flat portion 141. Formed integrally with said flat portion 141 and flange 142 is an extension member 143 disposed in the same plane as the flat portion 141, said extension 143 terminating in an inwardly slanting edge 144, slanting at the same angle as the flanges 111 and 121 of the upper sash and flanges 79 and 88 of the lower sash. As will be noted from Figure 3, the plate 140 is bent upon itself at the end of the slanting edge 144, as indicated at 145, and pressed over against the underside of the slanting edge 144 and against a portion of the extension 143 and terminates in an inwardly extending flange 146, thus forming a chamber 147 between said inwardly extending flange 146 and the flange 142. Fixed to the end of the flange 146 is a plate 147' having a flange portion 148 and an inwardly extending slanting edge 149, said edge slanting at the same angle as the edges 114 and 124 of the upper sash and the edges 81 and 91 of the lower sash. The other end of the flat portion 141 is bent upon itself to form a flange 150 comprising a double thickness of material and extending at the same angle as the flange 142, and formed integrally with said flat portion 141 and flange 150 is an extension 151 disposed in the same plane as the flange portion 141 and extension 143, said extension 151 terminating in an inwardly slanting edge 152 slanting at the same angle as the edges 111 and 121 of the upper sash and flanges 79 and 88 of the lower sash. This slanting edge 152 terminates in an inwardly extending flange 153.

The vertical edges of the sashes 26 and 29 which meet the vertical edges of the sashes 27 and 30 will now be described. Joining the upper and lower cross bar members of said sash sections 26 and 29 is a plate indicated at 154 consisting of a flat portion 155, a looped portion 156, a base portion 157 provided with a flat side portion 158, which side portion 158 terminates in an inwardly slanting edge 159, disposed at the same angle as the edges 111 and 121 of the upper sashes 130.

and edges 79 and 88 of the lower sashes. Fixed to one end of the base portion 157 is a plate 160 having a flange portion 161 and terminating in an inwardly slanting edge 162, slanting in the same angle as the edges 114 and 124 of the upper sashes and edges 81 and 91 of the lower sashes. The other end of the flat portion 155 is also bent upon itself to form a looped portion 163 and an upwardly extending flange 164.

The vertical edges of the sashes 25 and 28 which meet the vertical edges of the sashes 26 and 29 are similarly constructed to the vertical edges of the sashes 26 and 29 which meet the vertical edges of the sections 27 and 30 just described and indicated generally at 154.

The vertical edges of the sashes 26 and 29 which meet the vertical edges of the sashes 25 and 28 are constructed similarly to the vertical edges of the sections 27 and 30 which meet the vertical edges of the sections 26 and 29 as indicated generally at 140.

Referring to Figures 8, 11, 16 and 17, the mounting of the sash sections on the sliding frames will now be described, each sash section being mounted similarly. Through the larger opening 62' in the upper wall 61 is mounted a bushing or tubular form 167, as shown in Figures 8 and 11, said bushing being formed of very strong and durable metal. One end of said bushing rests on the upper surface of the lower wall 62, the other end extending through the opening 62' and formed with a collar 168 resting on the upper wall 61. The horizontal bar members 104 and 115 of the upper sashes also are provided with openings at their ends in alignment with the openings 62' of the sliding frame. The upper walls 105 and 116 of the upper and lower horizontal bar members of the upper sash section, and the upper walls 72 and 83 of the upper and lower horizontal bar members, respectively, of the lower sash section, each has formed around said aligned openings, a downwardly depressed portion 169, which depressed portion is adapted to rest upon the collar 168 of said bushing 167, leaving a space between the upper walls 105 and 61, and between the upper walls 116 and 61, and the upper walls 72 and 61, and the upper walls 83 and 61 to prevent frictional engagement of said walls when the parts move. A washer or tubular form 170 is placed between the upper surface of the lower wall 106 and the lower wall 62 and between the upper surface of the lower wall 117 and the lower wall 62, and between the upper surface of the lower wall 73 and the lower wall 62 and between the upper surface of the lower wall 84 and the lower wall 62 to space these walls apart to prevent frictional engagement when said parts move. A pin or bolt 171 extends

through the aforesaid aligned openings, the bushing 167 and washer 170, the ends of said pin being securely embedded in the lower and upper walls of the horizontal bar members, thus preventing displacement of the parts and permitting the sash sections to swing around said pin as shown in Figures 2 and 16.

An important feature of the present invention is the provision of means for facilitating the raising and lowering of the sash sections. This means as will be seen from Figures 6 and 15 comprises a handle indicated at 172 which is formed integrally with the web portion 85 of the cross bar members 82 by striking out a portion of said web portion. This handle 172 is curved to conform to the curvature of the hand of the operator to facilitate gripping the same.

Each of the sashes carries a pane of glass 173 and the novel means for holding and centering this glass and for holding a supply of putty therearound is an important feature of the present invention. It will be noted that the vertical and horizontal sections of the sashes with their slanting edges form a substantially U-shaped pocket 174 for holding a supply of putty 175; and that the ends of the slanting edges slant toward each other forming a restricted opening 176. The edge of the glass 173 extends through said restricted opening 176 and into the pockets 174, the ends of the slanting edges impinging against the surface of the glass. By reason of this construction, the glass is centered with respect to the pocket and a uniform supply of putty is placed around the glass. A weather proof joint is formed preventing air or weather from reaching the putty and also protecting the putty from falling out of the window when it becomes dry.

The means for locking the sash sections is illustrated in Figures 1 and 18 and comprises a lock consisting of a plate 177 adapted to swing on a pin 178 mounted in the upper and lower horizontal bar members of the sashes, and provided with a finger grip 179. A hook portion 180 is formed integrally with the plate 177 and extends downwardly therefrom and is adapted to engage a pin 181 mounted in the openings 66 of the channel portions of the sliding frames to hold the parts in locked position. Preferably one of these latches is provided at the top of the upper sash section or section 25, another at the bottom of this section 25, and still another at the top and bottom of the sash section 26, all of these latches being alike in construction. They serve the purpose of locking the sash sections 25, 26 and 27 to the sliding frame 23 to prevent said sections from swinging inwardly except when the latch is released, and they are also mounted on and also serve to prevent the

sections 28, 29 and 30 from swinging inwardly except when the latches are released.

If desired, rods 182 may be pivotally mounted between the upper cross bar members of the sections and the cross bar members of the sliding frames to adjustably hold the sash sections in opened position as shown in Figure 2. These rods are disposed between the upper and lower walls of the cross bar members of the sliding frames when the sash sections are in closed position as will be understood.

Another feature of the invention is provision of means for housing the chain which holds the window weight. As will be seen from Figure 17, mounted between the side walls 69 and outer wall 70 and disposed in the channel 70' of the side posts 68 is a pin 183 and secured to said pin is a hook 184.

A chain 185 which holds the window weight (not shown) is releasably secured to said hook by inserting one of its links there-around. By reason of this arrangement the chain 185, which passed downwardly through the opening 41, is disposed interiorly of and spaced away from the walls of said post and is thus housed by said walls and prevented from becoming jammed with other elements thereby assuring freedom of movement.

It will be noted from Figure 17 that the upper and lower walls 61 and 62, respectively, terminate in curved edges 61' at a point removed from the end of the web portion 61 as hereinbefore described. By reference to Figure 4, it will be seen that a curved cover 186 is supported by the curved edges 61' and covers the end of the channel 63'. This cover 186 is provided with a downwardly slanting portion 187 which terminates in a straight portion 188 extending into the channel 63'. The horizontal cross bar members at their pivotal ends are formed with a cut-out portion indicated at 189 so that when said cross bars are in closed position the said cut-out portion surrounds the cover 186 and the extreme end indicated at 190 of the web portions of the cross bars engages the slanting portion 187 of said cover, the inner surface of said web portion engaging the extension 188 thereby completely closing the channel 63' and forming an air tight juncture.

Referring to Figures 5 and 10, each of the front walls 44 with their slanting walls 49 of the side posts 22 is provided with an opening 191, said opening extending from a point a little removed from the bottom of the post to a point slightly above the center of the post, and extending in width from a point indicated at 44' near the extreme end of the side wall 44 to a point at the remote side end of the slanting wall 49. This opening is sufficiently large to receive one end of the sliding frame. The opening 191 is

covered by a plate 192, which plate consists of a flat portion 193 and a slanting portion 194, the surfaces of said flat and slanting portions being on the same planes as the surfaces of the walls 44 and 49, respectively. Fixed to the inner surface of the slanting wall 194 is a plate 195 provided with a flange 196. When the plate 192 is placed over the opening 191, the flange portion 196 engages the flange portion 49', and abuts against the shoulder 47, and the extreme end indicated at 197 of the slanting portion 194 abuts against the inner edge of portion 49', and the extreme end of the flat portion 193, indicated at 198, abuts against the edge 44' of the front wall 44. Angle irons 199 are mounted at the corners where the front walls 44 and side walls 42 intersect, at spaced intervals in the opening 191, one portion of said angle iron protruding above the edge 85 of the opening to which protruding portion the lower end of the plate 193 is secured. By reason of this construction the plate 192 is securely held and a uniform surface is presented.

In assembling the window, the jams or posts 22 and lower sill 20 and upper sill 21 are joined to form a unitary structure. The plate 192 from one of the side posts 22 is then removed presenting the opening 191. The width of the sliding frames being greater than the width between the end portions of the side posts 22, one end of the upper sliding frame is inserted into said opening 191 a sufficient distance to permit the other end of said frame to move upward and past the front wall 44 to its proper position. The plates 53 are then mounted in position on both sides of the jams and the extreme ends 57 of said plates hold the upper sliding frame from displacement. The lower sliding frame is next positioned by inserting one end thereof in the opening 191 permitting the other end thereof to pass the front wall 44 and become positioned in its proper position. The plate 192 is then replaced to close up the opening 191. The plate 51 is then placed in position over the wall 44 thereby covering up the plate 192 and at the same time holding the lower sliding frame in place against displacement. When the frames and sashes are thus assembled, the sash may then be swung upon its pivot pins 171 and the flange 134' of the plate 132 of the sash would then move out of the restricted portion 52' and swing freely between the cross bars 60 and 67, to the position shown in dotted lines in Figure 13. The curving of the portions 52 of the plate 51 permits the end edge indicated at 200 of the horizontal cross bar members to swing clear without touching said curved portions 52, and affords better locking means with the flanged portions 134'. It will also be seen from Figure 13 that a

5 curved spring member 201 formed of metal or other suitable material is secured to one of the side walls 69 of the sliding frames, the free end of said spring coacting with the flange portion 184' in its movement, and the engagement of said spring and flange portion forming an air tight joint at this point.

10 Another important feature of the present invention is means for grinding the abutting plates of their relative positions. This means is shown in Figures 6, 8, 13 and 14. Referring to Figures 6, the upper wall 83 is provided with an opening for the reception 15 of a screw 202, the upper surface of said wall surrounding said opening is raised or upset as indicated at 203, said raised portion 203 being internally screw threaded and with the threads on the said opening 20 affords additional means for engaging the threads on the screw 202, thereby more securely holding said screw. The plate 89 is formed with an opening 204 having a diameter greater than the diameter of the raised 25 portion 203 so that said opening 204 can be readily placed over said raised portion 203 as appears from Figure 6. The thickness of the plate 89 is such that when it is in position over the wall 83, the upper surface 30 of said plate 89 extends above the upper surface of the raised portion 203 so that when the screw 202 is driven home the head of said screw rests upon the upper surface of said plate 89 thereby jamming said plate 35 89 against the upper wall 83 to hold the same in place. The same construction is provided throughout the window wherever a screw is mounted, and by reason of this construction only one threaded opening for 40 receiving a screw is presented thus eliminating the aligning of several openings as is customary. The screws 202 for securing the plate 51 to the front wall 44 as shown in Figures 13 and 14 are spaced in staggered relation thus affording rigidity and strength at this point.

45 In operation, the lower sliding frame 24 is raised above the bead on the lower sill at the same time disengaging the rails where 50 the upper and lower sashes meet. The sashes mounted on said frame 24 may then be swung into the room and both sides of the pane of glass may then be cleaned as will be understood. The upper sliding frame 23 is 55 then lowered to align with the sliding frame 24, and the sashes mounted on said sliding frame 23 being shorter than the space between the cross bars 60 and 67 of the lower 60 frame 24 they are, therefore, permitted to swing into the room through the lower sliding frame 24, thus permitting the cleaning of both sides of the pane of glass as will be understood, eliminating the necessity of sitting or standing on the outer sill for the

purpose of cleaning the outer panes, and also affording 100% ventilation if desired.

When the window is closed, it will be noted from Figure 11 that the sash which meets the lower sill completely conceals the 70 bead 83 by reason of the extension plate 96. This is a very important feature of my invention. Heretofore, so far as applicant is aware, whenever wind or weather struck the bottom sill at the point where the sash meets 75 the beaded portion of said sill, it always found its way into the room, this point proving to be the weakest point in window construction and from a practical point of view it has been impossible to make the window 80 weather proof at this point. Applicant has provided an extension plate on that portion of the sash which meets the sill, which plate is at an angle to the horizontal so that when wind or rain strikes this particular point it 85 strikes the angle portion of the plate and not the lower sill at the beaded portion, said angle portion acting as a shield making a positive airtight and weathertight juncture at this point. 90

While I have illustrated and described one embodiment of my invention, it will be understood that changes may be made in details and arrangement of parts without departing from the principle of the invention, and I desire to be limited only by the state of the prior art and the appended claims. 95

I claim:

1. A window comprising a casement, 100 frames slidably mounted in said casement, end and intermediate sashes pivotally mounted on said frames, said intermediate sashes formed with cutout portions to permit the swinging of said sashes. 105

2. A window comprising a casement, frames slidably mounted in said casement, sashes pivotally mounted on said frames and means disposed between the meeting edges of said frames and casement to prevent jamming at said points. 110

3. A window comprising a casement, frames slidably mounted in said casement, sashes pivotally mounted on said frames and flexible means disposed between the meeting edges of said frames and casement to prevent jamming at said points. 115

4. A window comprising a casement, sashes for holding glass mounted in said casement, means carried by said sashes for centering said glass, said means provided with inclined portions resting against said glass. 120

5. A window comprising a casement, sash frames mounted in said casement, 125 sashes for holding glass mounted in said frames, means carried by said sashes for centering said glass, said means provided with inclined portions resting against said glass. 130

6. A window comprising a casement, sash frames mounted in said casement, sashes for holding glass mounted in said frames and a pocket carried by said sashes to hold 5 putty around the edges of said glass, said pocket provided with means to prevent the displacement of said putty.
7. A window comprising a casement, sash frames slidably mounted in said casement, a U-shaped post forming the side of 10 said frames and a pin secured to the interior of said U-shaped post and adapted to releasably hold the end of a chain.
8. A window comprising a casement, a sash frame slidably mounted in said casement, a sash hingedly mounted in said frame including upper and lower cross bar members and a plate carried by said sash and adapted to move between said cross bar 15 members during the hinging of said sash.
9. A window comprising a casement, a sash frame slidably mounted in said casement, a sash hingedly mounted in said frame including upper and lower cross bar members and a plate mounted on the inner vertical edge of said sash, said plate being adapted to move between said cross bar members during the hinging of said sash.
10. A window comprising a casement, including upper and lower sills, sliding 20 frames mounted in said casement, sashes pivotally mounted on said frames, each of said sashes including a lower horizontal bar member and a plate mounted on said lower horizontal bar member said plate having 25 extensions adapted to overlap the lower sill.
11. A window comprising a casement having upper and lower sills, said lower sill formed with a depressed portion, sliding 30 frames mounted in said casement, sashes hingedly mounted on said frames, each of said sashes including a lower horizontal bar member and a plate extending outwardly from said lower horizontal bar member and adapted to rest in said depressed portion 35 when the sash section is closed.
12. A window comprising a casement having side posts, sliding frames mounted in said casement, said frames being greater in 40 width than the width between the said posts, said posts formed with an opening adapted to receive the ends of said frames for positioning the same in the casement.
13. A window comprising a casement, 45 sliding frames mounted in said casement, said frames including upper and lower horizontal bar members formed with a channel, sashes hingedly mounted in said frames, a cover positioned over the ends of said channel, said sashes formed with upper and lower horizontal bar members, said bar members consisting of upper and lower walls and a web portion, said web portion 50 formed with a cut-out portion adapted to be positioned around said cover, the remainder 55 of said web portion adapted to close said channel when the sash is in closed position.
14. A window comprising a casement including side posts, frames slidably mounted in said casement, said side posts comprising front, rear and side walls, said front wall 60 formed with a depressed portion, a plate secured to the face of said front wall, said plate terminating in a curved portion extending midway of said depressed portion, and another plate fixed to the face of said depressed portion and terminating in a curved portion and disposed in the same plane as the first mentioned curved portion, 65 said front wall and said plates forming channels, and frames carried by said casement and adapted to slide in said channel and sashes hingedly mounted on said frames.
15. A window comprising a casement, upper and lower frames slidably mounted 70 in said casement, sashes mounted in said frames, said sashes including upper and lower horizontal cross bar members and means for raising said frames formed integrally with said sashes.
16. A window comprising a casement including a bottom sill, said casement formed with slots, slidable frames guided by said slots, said frames adapted to engage a portion of said bottom sill when in closed position, means carried by said sash frames 75 adapted to conceal the engaged portion of said sill.
17. A window comprising a casement, including upper and lower sills, frames mounted in said casement, means carried by said frames adapted to engage said lower sill when in closed position.
18. A window comprising a casement including upper and lower sills, slidable 80 frames mounted in said casement, means carried by said frames adapted to engage a portion of said lower sill when in closed position, means formed on said sill at 85 said engaging portion to engage a portion of said frame when in said closed position.
19. A window comprising a casement, sashes for holding glass mounted in said casement and pockets having inclined walls 90 formed on said sashes for securely holding putty around the edges of said glass.
20. A window comprising a casement, frames slidably mounted in said casement, sashes pivoted on said frames and means to keep the sashes and frames spaced apart.
21. A window comprising a casement, frames slidably mounted in said casement, sashes pivoted on said frames and means disposed between the sash and frames at their pivot point to keep the sashes and frames apart.
22. A window comprising a casement, frames slidably mounted in said casement, sashes pivoted on said frames and means comprising a tubular form associated with

said frame and sashes to keep the frames and sashes apart.

23. A window comprising a casement consisting of an upper and lower sill, the upper sill consisting of a flat portion having a slot therein and sashes slidably mounted in said casement.

24. A window comprising a casement consisting of an upper and lower sill, the upper sill consisting of a flat portion having a slot and sashes slidably mounted in said casement and interlocking with said slot when in closed position.

25. A window comprising a casement consisting of an upper and lower sill, the upper sill consisting of a flat portion having a slot with its edges bent upwardly, and sashes slidably mounted in said casement and interlocking with said slot when in closed position.

26. A window comprising a casement consisting of an upper and lower sill, the upper sill consisting of a flat portion having a slot, frames slidably mounted in said casement, sashes pivotally mounted in said frames and interlocking with said slot when in closed position.

27. A window comprising a casement consisting of an upper and lower sill, the upper sill consisting of a box having one of its walls removable, frames slidably mounted in said casement and sashes pivotally mounted on said frames.

28. A window comprising a casement consisting of an upper and lower sill, the upper sill consisting of a box having one of its walls removable and frames slidably mounted in said casement.

29. A window comprising a casement consisting of an upper and lower sill, the upper sill consisting of a box having its edges converging and looped, a plate having edges bent over and converging, said plate having its edges slidably mounted in said box, frames slidably mounted in said casement.

30. A window comprising a casement consisting of an upper and lower sill, the upper sill consisting of a box formed with a slot and spaced openings disposed from said slot for receiving the chain for the weight and frames mounted in said casement.

31. A window comprising a casement including side chambers and upper and lower sills, frames slidably mounted in said casement, said side chamber comprising front and side walls, the edges of said side walls looped and converged and a plate having its edges converging and slidably mounted within said looped portion of said side walls.

32. A window comprising a casement including side chambers and upper and lower sills, frames slidably mounted in said casement, said side chamber comprising front and side walls, and a plate slidably mounted

in said side walls, said plate formed with a loop.

33. A window comprising a casement including side chambers and upper and lower sills, frames slidably mounted in said casement, said side chambers consisting of front, side and rear portions, one of the side portions formed with an extension portion.

34. A window comprising a casement including side chambers and upper and lower sills, frames slidably mounted in said casement, said casement including side and front portions, said front portion having a depressed portion formed with an offset portion, a plate mounted in said depressed portion positioned against said offset portion.

35. A window comprising a casement including a side chamber and upper and lower sills, frames slidably mounted in said casement, said side chambers consisting of a side and front portion, said front portion having a depressed portion, a plate secured to said depressed portion and means on said depressed portion for guiding the mounting of said plate.

36. A window comprising a casement, frames slidably mounted in said casement, sashes pivotally mounted on said frames, said frames and sashes formed with aligned openings when in operative position, a bushing disposed in said aligned openings, a pin mounted in said bushing and a washer carried by said pin and adapted to hold said frames and sashes in spaced apart relationship.

37. A window comprising a casement, frames slidably mounted in said casement, sashes pivotally mounted on said frames, said frames and sashes formed with aligned openings when in operative position, a bushing disposed in said openings, a shoulder formed on said bushing, a pin mounted in said bushing, the edges of the opening in said frames being angularly disposed and adapted to result upon the shoulder of said bushing to prevent frictional engagement of said frame and sashes.

38. A window comprising a casement, frames slidably mounted in said casement, sashes pivotally mounted on said frames, said frames consisting of a web portion and upper and lower portions, said upper and lower portions formed with aligned openings, the diameter of the opening in the upper portion being larger than the diameter of the opening in the lower portion, a bushing disposed in said openings, said sashes consisting of a web portion and upper and lower portions, aligned openings in said upper and lower portions, a pin disposed in said sash openings and said bushing and formed with a head portion riveted to the lower portion of the sash to prevent displacement.

39. A window comprising a casement, sash

frames mounted in said casement, sashes for holding glass mounted in said frames, said sashes including upper and lower horizontal cross bars and vertical angle bars, inwardly inclined edges formed on said bars, a plate secured to said bars and an inwardly inclined edge formed on said plate, the extreme ends of said inclined edges forming a guide for centering the glass held by said sashes.

40. A window comprising a casement, frames within said casement, said frames having inclined means for holding glass therein said inclined means being adapted to rest against said glass to prevent side movement of said glass.

41. A window comprising a casement, frames within said casement, said frames having means for holding glass therein said means having inclined walls for holding the glass against side movement.

42. A window comprising a casement, frames within said casement, said frames having means for holding glass therein, said means having inclined walls for centering said glass and for holding same against side movement.

43. A window comprising a casement, frames within said casement, said frames having means for holding glass therein, said means having inclined walls for holding the glass against side movement and securely holding putty around the edges of said glass.

44. A window comprising a casement, frames within said casement, sashes within said frames, said sashes having means for holding glass therein, said means having inclined walls for holding the glass against side movement.

45. A window comprising a casement, frames within said casement, sashes pivotally mounted in said frames, said sashes having means for holding glass therein, said means having inclined walls for holding said glass against side movement and securely holding a cementitious substance around the edges of said glass.

46. A window comprising a casement, sliding frames within said casement, extensions on said frames and flexible means carried by one of said extensions to prevent jamming of said frames when being closed.

47. A window comprising a casement, sliding frames within said casement, an extension formed on one of said frames, a spring carried by said extension, an extension formed on the other frame and adapted to engage said spring when closing the same to prevent jamming.

48. A window comprising a casement, sliding frames within said casement, an extension formed on one of said frames, a spring carried by said extension and having a free end, a flange formed on said extension and adapted to engage said free end, an ex-

tension formed on the other frame adapted to engage said spring and said flange portion.

49. A window comprising a casement, sliding frames within said casement, an extension formed on one of said frames, a curved spring carried by said extension and having a free end, a flange formed on said extension and adapted to prevent displacement of said free end, an extension on the other frame formed with a downwardly extending flange portion adapted to engage said curved spring when in closed position.

50. A window comprising a casement, frames mounted on said casement, the bottom of said frames formed with a channel portion, one wall of said channel portion formed with a flanged portion, the edge of said flanged portion formed with a curved portion.

51. A window comprising a casement, frames mounted on said casement, the bottom of said frames formed with a channel portion, both walls of said channel portion formed with flanged portions.

52. A window comprising a casement, frames mounted on said casement, the bottom of said frames formed with a channel portion, one wall of said channel portion formed with a flanged portion extending outwardly and the other wall of said channel portion formed with a flanged portion extending inwardly.

53. A window comprising a casement, frames mounted on said casement, the bottom of said frames formed with a channel portion, and a curved spring mounted in said channel portion.

54. A window comprising a casement, frames mounted on said casement, the bottom of said frames formed with a channel portion, one wall of said channel portion formed with a flange, a spring secured at one end to said flange, the free end of said spring adapted to engage the other wall of said channel portion.

55. A window comprising a casement, frames mounted on said casement, sashes mounted within said frames, said frames consisting of upper, lower and side portions, flexible means carried by said side portion, a curved plate mounted on said sashes and adapted to engage said flexible means when in closed position.

56. A window comprising a casement, frames within said casement, said frames consisting of upper, lower and side portions, sashes within said frames, flexible means carried by said side portion, a curved plate carried by said sashes and adapted to engage said flexible means when in closed position.

57. A window comprising a casement, frames within said casement, said frames including cross bars and channel portions

rigidly connected to form a unitary structure, and chains disposed in said channel portions for holding said frames to the casement.

5 58. A window comprising a casement having side posts, sliding frames mounted in said casement, said posts formed with an opening adapted to receive the ends of said frames for positioning the same in the 10 casement, means for closing said opening after positioning said frame.

59. A window comprising a casement including a cut-out portion, a removable plate, sliding frames in said casement, said 15 plate formed with a slanting edge at one end and a flange at its other end, said slanting edge engaging one edge of said cut-out portion, said flange engaging said other edge of said cut-out portion thereby covering 20 said opening.

In testimony whereof, I hereunto affix my signature.

JACOB L. KLEINMAN.
